CLAIM

The ornamental design for a floor joist lifter and positioner, as shown and described.

DESCRIPTION

FIG. 1 is a perspective view of a floor joist lifter and positioner, showing my new design;

FIG. 2 is a front view thereof;

FIG. 3 is a left side view thereof;

FIG. 4 is a right side view thereof;

FIG. 5 is a top view thereof;

FIG. 6 is a bottom view thereof;

FIG. 7 is a left side view thereof, with the upper portion shown in an alternate position for clarity of illustration; and,

FIG. 8 is a left side elevational view of a second embodiment of the lifter as disclosed in FIG. 1.

FIG 1
